UNITED STATES PATENT OFFICE.

GUSTAF W. HANSON, OF WICHITA, KANSAS.

BORING-DRILL.

1,398,551.

Specification of Letters Patent. Patented Nov. 29, 1921.

Application filed August 2, 1920. Serial No. 400,713.

To all whom it may concern:

Be it known that I, GUSTAF W. HANSON, a citizen of the United States, residing at Wichita, county of Sedgwick, and State 5 of Kansas, have invented certain new and useful Improvements in Boring-Drills, of which the following is a full, clear, and exact description.

The invention is applied particularly to 10 the rotary, motor operated type of boring drills, especially adapted for use in drilling oil and gas wells, and for other earth boring operations, and is designed to provide a compactly arranged, and self contained 15 power-unit and drill head that may be manipulated and operated with facility.

The invention involves certain novel combinations and arrangements of parts, and certain novel features of construction in the 20 rotary drill unit and drill head and their connections, including an elevated power unit and the drill head suspended therefrom, together with particular arrangements of parts in the drill head for suspending the 25 drill spindle and well casing.

By the utilization of my invention, the well casing which accompanies the drilling stem and bit, is lowered simultaneously with the drilling tool as fast as the latter digs 30 into the ground, thus eliminating the danger of caving in of the walls, as the boring progresses. In a co-pending application for patent, Serial No. 400,712, filed August 2, 1920, means are illustrated whereby the feed 35 of the casing and stem are automatically regulated.

Provision is made for an improved circulation of water whereby the cuttings from the drill bit are removed through the well 40 casing, and the increased flow of water that results from the use of my invention, by hydraulic action, enhances the cutting operations of the bit.

In the accompanying drawings I have 45 illustrated one complete example of the physical embodiment of my invention in which the parts are combined and arranged according to the best mode I have thus far devised for the practical application of the 50 principles of my invention.

Figure 1 is a view in side elevation of the

rotary power unit and aligned drill head and connections for operating the drill stem.

Fig. 2 is an enlarged, vertical sectional view, showing the drill head and connections. 55

Fig. 3 is a transverse sectional view through the overflow basin, on line 3-3 of Fig. 12.

Fig. 4 is a detail view, in section, of the coupling chuck connected to the extra sections of the drill stem during drilling operations. 60

Fig. 5 is a transverse sectional view on lines 5-5 of Fig. 4 of the coupling chuck.

Fig. 6 is a sectional view of the drill head 65 beam at line 6-6 of Fig. 1.

Fig. 6^a is a detail view, partly broken away, showing the drill chuck and an auxiliary tool or connecting wrench employed in the process of connecting extra 70 sections to the casing.

Fig. 7 is a top plan view of the connecting wrench to be used in conjunction with the chuck for making or withdrawing connections in the casing. 75

Fig. 8 is a view in side elevation of the wrench.

Fig. 9 is a transverse sectional view through the drill head on line 9-9 of Fig. 2 showing the inlet to and flow of water from 80 the head.

Fig. 10 is a detail showing a face view of one of the guide rollers for the movable feed frame.

Fig. 11 is a transverse sectional view on 85 line 11-11 of Fig. 1 illustrating one of the guide rollers and its runway for the movable frame.

Fig. 12 is a view partly in elevation and partly in section of the overflow basin and 90 water outlet therefrom.

Fig. 13 is a detail sectional view at line 13-13 of Fig. 6^a, showing the drill chuck sleeve keyed to the drill spindle to prevent relative movement of the parts. 95

In the preferred form of my invention as illustrated in the drawings, reference may be had to the general assembly view of Fig. 1 in which the essential elements of the invention are depicted and their combination 100 and arrangement shown.

In carrying out the purpose of my inven-

tion I utilize a rectangular frame 1 that is movable with the feed of the drilling tools, and guided by means of the two columns 2, 2 that are erected centrally of a derrick 5 or tower of the drilling outfit, part of the transverse frame of the tower being indicated at 3, 3, of Fig. 1.

Rollers 4, 4, are journaled on the movable frame to facilitate the movement of the 10 frame in its descent as the drilling proceeds and to guide the apparatus when withdrawing or elevating the power unit, to add extra sections to the well casing and drill stem.

The power for the drilling machine is 15 provided by an electric motor 6, with wires 6' extended to a source of supply on the ground, and the motor is rigidly attached to the movable frame 1 by brackets 7, 7. The frame 1 is made up of channel iron 20 beams and the brackets are fitted into the channels and bolted or riveted therein.

The power unit, although described herein as an electric motor, may be of other 25 types, such as an internal combustion engine, pneumatic motor, or steam operated machine, arranged in vertical alinement with the drilling mechanism, and in connection with the electric motor I utilize a gear within the casing 8 alined with the 30 armature shaft 9 of the motor to reduce the rotary movement of the motor from high speed for revolving the transmission shaft 10 of the drill head.

A safety device or clutch 11 is used in the 35 transmission of rotary power to the operating parts of the drill head, which clutch is indicated as a whole by the numeral 12.

The movable frame is located centrally 40 of the derrick or tower and is designed to descend as the drilling operations proceed, and to be elevated or hoisted toward the upper end of the tower after the drill head is disconnected from the well casing and drill 45 stem preparatory to the addition of extra sections of casing and stem.

To guide the movement of the frame, the 50 rollers 4 run in the trackway formed by the H-beams, as best seen in Fig. 11, and preferably angle irons 13 are riveted to the opposite edges of the H-beams to form retaining flanges for the rollers 4, 4. The frame is thus guided in its movement and retained in proper alinement with the drilling tools or devices operated from the motor.

55 The transmission clutch or safety device 11 (Fig. 1) is of the well known pin-belt type employing a driving disk 14 on the transmission shaft 10, with pins 15 depending therefrom, and a complementary disk 16 with upwardly extending pins 17. These 60 two sets of pins are arranged on concentric lines about the center of the disks, with a leather belt 18 intertwined between them. Should an excessive resistance to the rotary 65 movement of the motor be encountered for

any cause in the drilling tool below the clutch, the latter, which is the weakest point in the power transmission devices, will be broken before damage can come to the drilling tool beneath the safety clutch.

70 The beam 19 for supporting the drill head is a metal casting of inverted U shape, as seen in Fig. 6, with its ends projecting into the channels of the opposed channel iron beams of the frame 1, and the transverse beam 19 is rigidly secured, as by bolts or rivets, to the two side bars of the frame 1.

The cross beam 19 is fashioned with a vertically extending integral, central, cylindrical element 20, forming the water inlet 80 chamber for the introduction of water from the inlet boss 21, to which is attached the inlet hose or pipe (not shown). The upper end of this chamber is closed by a transverse ring 22 formed with a depending central thimble 23, and below the water chamber 24, a sleeve 25 is formed, having an end flange 26.

The hollow drill spindle 27 is revolvably supported in this specially designed cross 90 beam 19, by the packing gland 28 and its flanged end cap 29, bolts 30 being used to form a close joint about the spindle.

An annular series of bearing rollers 31 is interposed between the cup 32 of the packing gland and the spindle, and annular packing rings 33, of felt, may also be utilized.

At its upper end the hollow spindle is formed with a solid shaft portion 34, an annular shoulder 35, a threaded extension 100 36, and a reduced threaded end boss 37. The boss 37 is threaded into sleeve 38 of the driven disk 16 of the transmission safety clutch 11, and the extension 36 receives the bearing plate 39.

The strain of transmitting rotary motion from the driven disk to the drill head is taken by the series of four bolts 40 passed longitudinally through the sleeve 38, plate 39 and threaded into the shoulder 35 of the 110 drill head shaft, and these bolts hold the head 38 from unscrewing during reverse action of the head. It will thus be apparent that the disk 16, plate 39 and shaft 34, form a rigid structure that is revolvable in the drill head under power from the motor.

Two annular sets of ball bearings as 40 and 41, are provided, one below and the other above the bearing plate 39, the usual grooved bearing rings 42 being employed 120 and retained in their places by the head-plate 43 and bolts 44 passed through the flange 45 of the drill-head beam 19.

The water inlet 21 to the inlet chamber 24 is located below the bearings for the shaft 125 in the drill head, and the water is supplied to the interior of the hollow drill spindle 37 through ports 46 therein and ports 47 in a packing sleeve 48 interposed between the gland 28 and the internal sleeve 23 of 130

the water chamber 24. Flexible metallic packing 49 is provided to form a close leak proof joint. The flow of water for circulation to the bottom of the well is indicated 5 by the arrows in Fig. 9, and it will be apparent that the currents of water flow through the inlet boss 21, from an attached hose, thence through the ports 47 and 46 to the bottom of the hollow spindle, and then 10 the water descends to the bottom of the well through the drill stem 50.

At the lower end of the hollow drill spindle, a chuck, indicated as a whole by the numeral 51, is utilized as the connection between 15 the drill spindle and drill stem 50. As best illustrated in Figs. 1, 4 and 13, the spindle 27 is threaded into the collar 52 of the chuck and a transverse key 53 passed through a slot in the collar and a groove 20 in the spindle is utilized to lock these parts against displacement.

The stem 50, which may be a 4" pipe or casing, is entered up through the bottom of the chuck, and threaded into the base of 25 the collar 52 at 54, and is positively held in the head 55 of the chuck by a pair of opposed jaws 56 and 57. These jaws, it will be noted, are fashioned with curved, toothed faces or racks 58 and 59, arranged in opposite 30 directions, in order that one jaw may positively engage the periphery of the cylindrical drill stem and co-act with its complementary jaw, when revolving the stem in one direction, as for the drilling operations. The drilling operations depend upon 35 the threaded connection to drive the jaws and transmit rotary motion, and this action of the jaws is supplemental thereto. When the rotary motion of the chuck is reversed or 40 for quick connections in screwing on sections of the drilling stem, the other jaw is effective in its engagement with the periphery of the drill stem.

The two jaws are slidable in the radial 45 recesses 60 in the chuck head and are forced against the stem by the action of the pair of wedge keys 61 which slide tangentially of the stem in their slots 62 of the chuck head. Wedge shaped keys 63 may be employed 50 to lock the slotted wedge keys in place in the drill head and the locking keys are passed through slots in the base plate 64 of the chuck 51.

From the above description it will be understood 55 that the successive drill stem sections 50 are added to the drill stem and secured at their top ends to the chuck, and that the rotary motion of the motor is transmitted to the drill stem through the instrumentality of the drill spindle shaft and the chuck as described.

A drilling bit (not shown) is attached at the lower end of the drill stem, to cut away 60 the ground structure at the bottom of the well, and such a drill bit forms the subject

matter of a copending application for Patent Serial No. 398,785 filed July 24, 1920.

The well casing 65 is of larger diameter than the drill stem and surrounds the stem. The casing is made up of the usual sections, 70 corresponding in length to the sections of the drill stem, and is suspended from the drill-head beam 19 through the instrumentality of a pair of arms 66 and 67, each pivoted on a headed pin 68 passed through the beam, which is perforated for the purpose, and secured therein by a key 69. Near the lower ends of the suspending arms 66 and 67 are provided a series of spaced perforation 70, to receive the attaching bolts 71, by 80 means of which the cross head 72 may be adjustably attached to the arms.

The cross head is a steel casting with forked ends or pairs of lugs 73 to accommodate the flat arms 66 and 67 therebetween. 85 The body of the cross head 72 is fashioned as a cylindrical, open, vertically disposed cup 74, and is of sufficient strength to form a rigid and stable connection between the two suspending arms, for holding the lower 90 end of the drill head in alinement with the power unit supported thereabove.

Within the cup 74 is provided an integral, central, annular flange 75, and above the cup is located the overflow basin 76 having an 95 exterior annular shoulder 74' fitting over the top peripheral edge of the cup and closing the same. The top 77 of the basin is perforated for reception of members of a wrench or tool, to be described, for rotation 100 by the wrench, and the bottom 78 of the basin is provided with an annular series of ports 79 for passage of water from the basin to the interior of the cup.

In the bottom of the basin a downwardly 105 projecting sleeve 80 is provided, which, at its upper end, rises above the basin bottom and by a return bend 81 is integrally joined thereto, thus fashioning an annular recess or socket 82 to slip over the upper edge of 110 the flange 75 of the cup and inclose the same.

At its lower end, which projects below the body of the cross head, the sleeve 80 is threaded to receive an enlarged nipple, or 115 flanged open bushing 83, and a lock screw 84 may be used to hold these parts from unscrewing. The lower end of the bushing has an open extension or thimble 83' to which a coupling sleeve 85 of the well casing 120 65 is also screwed.

It will be obvious that in addition to forming a brace and support for the well casing and drill, the cross head also forms the overflow device for disposing of the water 125 as it rises in the well casing from the bottom of the well. Thus in Fig. 12 the arrows indicate the descent of the water in the drill stem 50, and other arrows designate the ascent of water in the well casing outside the 130

stem. The ascending currents pass through the well casing, coupling, and sleeve 80 to the interior of the basin 76, thence down through the ports into the cup and flow around the cup and out through port 86 and nozzle 87 cast upon the bottom of the cup, and the water may be conveyed to the sump by a hose (not shown) attached to the nozzle.

10 In a co-pending application for patent Serial No. 398,784 filed July 24, 1920, I have illustrated mechanism including a jib crane supported on a derrick or tower by means of which the additional well casing sections 15 and drilling stem sections are prepared and swing to position for attachment to the casing and stem as the drilling proceeds. In Figs. 6^a, 7, and 8 of the present case I illustrate a wrench or tool employed in the process 20 of disconnecting the drill head from the well casing thus disengaging the drill head preparatory to changing the well casing and drill stem sections.

The wrench is designated as a whole by 25 the numeral 88 in Figs. 7 and 8 and comprises openable jaws 89, 89 with interlocking perforated ears 90, 90 to receive the detachable securing pins 91, 91. At opposed corners of the flat, diamond shaped tool are a 30 pair of dependent, fixed studs 92, 92, which are adapted to be inserted in the openings 93, 93 in the top plate 77 of the overflow basin 76 which is rigidly supported as described on the cross head 72.

35 The pins 91 of the wrench are of sufficient length to be passed through openings or grooves 94, 94 in the chuck head 55 (Figs. 5 and 6^a).

The wrench is placed in operative position 40 about the stem 50 by applying the open jaws 89 thereto and coupling the jaws together with pins 91 after passing said pins through openings 94 of the chuck head 55, and the studs 92 are lowered into the openings 93 45 of the overflow basin.

A wrench or holding tool (not shown) is now applied to the coupling sleeve 85 of the well casing to hold the same against rotary movement. The spindle 27 and chuck are 50 then revolved to unscrew the basin and its bushing 83 and thimble 83' from the stem coupling sleeve 85 (Fig. 12), the basin and its connected parts being free to revolve in the beam. By this means the drill head may 55 be disconnected from the well tube or casing, and after the chuck 51 has been unscrewed from the top of the drill stem 50 the frame 1 and its drill head, including the chuck, may be elevated to provide room for the additional tube section and drill stem section.

The chuck 51 is unscrewed from the top 60 of the drill stem 50, after the keys 63 and 61 have been loosened. But previous to turning the chuck on the stem the supporting arms 66 and 67 are disconnected from the

beam 72 by the removal of the bolts 71, and the arms are swung outwardly on their pivots 68 to permit the application of a wrench or similar tool (not shown) to the drill stem 50 just below the chuck and above 70 the overflow basin in Fig. 1. While the tool holds the stem, the spindle 27 and chuck are revolved, thus freeing the chuck from the drill stem.

Having thus fully described my invention, 75 what I claim as new and desire to secure by Letters Patent is—

1. The combination in a rotary drill head and its suspending frame including a cross beam, of supporting arms pivoted on said 80 beam, a cross head connecting the free ends of said arms and formed with an open top cup having an outlet, an overflow basin closing the cup and communicating therewith, said basin having a central sleeve projecting through the cup, and a well tube 85 communicating with said sleeve for the purpose described.

2. In a water-circulation device as described, the combination with an inclosed 90 drill stem, of a suitably supported member fashioned as an open cup and provided with an outlet, an overflow basin closing said open cup and communicating therewith, a sleeve on the basin projecting through the open 95 center of said cup, and a well casing surrounding said stem and communicating with said basin.

3. The combination with the open cup member having an outlet and a central annular flange, of an overflow basin closing 100 said cup and provided with a perforated bottom, a sleeve on said bottom fitted over said flange and projecting below the cup, a drill stem inclosed by said members, and a 105 well casing communicating with said sleeve, for the purpose described.

4. The combination with supporting arms, of a cross beam and means for securing said beam to said arms, said beam formed with a 110 cylindrical open cup having a central annular flange and an outlet from the cup, of an overflow basin having a perforated bottom closing said cup, a central sleeve formed with an annular socket and integral with 115 the bottom of the basin fitted over the top edge of said flange, a drill stem inclosed by the cup and basin, a nipple threaded on the end of said sleeve, a thimble on said nipple, a well tube surrounding the stem and a 120 coupling sleeve connecting said tube and thimble.

5. The combination in a rotary drilling machine, of a drill head and driven spindle, a drill stem connected to said spindle, a cross 125 beam supporting said members and fashioned with cylindrical walls forming a water inlet chamber, there being communication between said chamber and spindle for flow of water to the drill stem.

6. The combination with a rotary drill shaft having its lower end formed as a hollow drill spindle and a hollow drill stem secured to said spindle, of a supporting cross beam fashioned with cylindrical walls forming a water inlet chamber, a bearing sleeve integral with the beam, a packing sleeve between the spindle and said bearing sleeve, and said packing sleeve and spindle having 10 ports for passage of water from the chamber to said drill stem.
7. The combination in a rotary drilling machine with a supporting cross beam and rotary bearings therein, of a hollow drill 15 spindle and drill stem, said spindle having a solid shaft portion supported in said bearings, and means for furnishing circulation of water to said spindle and stem.
8. The combination in a rotary drilling 20 machine with its hollow spindle, of a coupling chuck secured at the lower end of said spindle, and means for connecting said chuck to a hollow drill stem, as described.
9. The combination in a rotary drilling 25 machine with a hollow spindle, and a coupling chuck connected to said spindle and, of an overflow basin, a supporting member and an outlet chamber therein for said basin, and means adaptable for connection between 30 said chuck and basin whereby the latter may be disengaged from a well casing.
10. In a rotary drilling machine the combination with a pair of perforated, pivoted, supporting arms, of a cross head having bifurcated and perforated ends connected to 35 said arms, said cross head fashioned with a cylindrical, open-top, overflow cup, an over-
- flow basin closing said cup and communicating therewith, and a well casing connected with said basin, for the purpose described. 40
11. The combination in a rotary drilling machine with a suspended driving mechanism and movable feed frame, of a drill head including a beam and suspending arms 45 thereon, a cross head connected to said arms and a well casing supported from said cross head, a drill stem within the casing, and connections between said stem and driving mechanism whereby the stem is operated 50 and the stem and casing are movable with the feed frame.
12. The combination in a rotary drilling machine with a suspended feed frame and driving mechanism supported thereon, of a 55 drill head alined with said mechanism and a driven spindle supported in said head, a drill stem connected with the spindle, a cross head rigid with the frame, and a well casing surrounding the stem and attached to said 60 cross head.
13. The combination in a rotary drilling machine with a suspended feed frame and driving mechanism supported thereon, of a drill head alined with said mechanism and a 65 driven spindle supported in said head, a drill stem connected with said spindle, a cross head rigid with said frame, a well casing surrounding the stem and attached to said cross head, means for introducing water 70 to said stem and means providing for egress of water from the well casing, forming part of said drill head. 70

GUSTAF W. HANSON.
